DESIGN FOR A DIAL HOUSING FOR A WEIGHING SCALE

Stan L. Hanssen, Andrew P. Olsen, and Albert
A. Schmid, Chicago, Ill., assignors to Marius
H. Hansen and Stan L. Hanssen, both of Chi-
cago, Ill.

Application September 27, 1937, Serial No. 71,824

Term of patent 14 years

To all whom it may concern:

Be it known that we, Stan L. Hanssen, Andrew
P. Olsen, and Albert A. Schmid, citizens of the
United States, residing at Chicago, in the county
of Cook and State of Illinois, have invented a
new, original, and ornamental Design for a Dial
Housing for a Weighing Scale, of which the fol-
lowing is a specification, reference being had to
the accompanying drawing forming part thereof.

Figure 1 is a perspective view of a dial housing
showing our new design.

Fig. 2 is a plan view thereof.

We claim:

The ornamental design for a dial housing for
a weighing scale, substantially as shown.
